J. M. Noble,

Bed Bottom,

No. 20,362.

Patented May 25, 1858.

UNITED STATES PATENT OFFICE.

JAS. M. NOBLE, OF DELHI, IOWA.

BED-BOTTOM.

Specification of Letters Patent No. 20,362, dated May 25, 1858.

To all whom it may concern:

Be it known that I, JAMES M. NOBLE, of Delhi, in the county of Delaware and State of Iowa, have invented a new and Improved 5 Bed-Bottom; and I do hereby declare that the following is a full, clear, and exact description of the same, reference being had to the annexed drawings, making a part of this specification, in which—

10 Figure 1, is a longitudinal section of a bed-bottom constructed according to my invention and applied to a bedstead. x, x Fig. 2 indicates the plane of section. Fig. 2, is a plan or top view of ditto. Fig. 3, is a 15 transverse section of ditto, taken in the line y, y , Fig. 2.

Similar letters of reference indicate corresponding parts in the several figures.

This invention consists in having a series 20 of pulleys attached to the head and foot rails of the bedstead by means of straps, ropes, or other flexible material, and having a rope pass around said pulleys, first around a pulley on one rail and then around a pulley on the other so that said rope will have 25 a serpentine form and fill the whole bottom, the several lengths of rope being connected by elastic bands to form lateral stays, and the whole arranged as hereinafter fully 30 shown and described so as to form an economical, durable and flexible bed bottom desirable in every respect.

To enable those skilled in the art to fully understand and construct my invention I 35 will proceed to describe it.

A, A, represent the head and foot rails of a bedstead to which wooden pins a , are attached, at equal and proper distances apart.

B, represents a series of pulleys which are 40 attached to the pins a , one to each, by means of cords or leather straps or other flexible material b , the cords or straps passing through the eyes of the pulleys B, and around the pins a . Other modes of attachment however may be used. A metal pin 45 may pass through the eyes of the pulleys, said pins being fitted in metal straps and the cords attached to said straps. Any mode of attachment may be employed that will allow 50 the pulleys to turn freely and at the same time permit them to swing and twist or turn in a plane at right angles to their plane of rotation, see red lines Fig. 3.

C, is a rope one end of which is attached

to a pin d , at one end of a rail A. This rope 55 passes around the pulleys B, alternately at either end of the bedstead and the pulleys B are placed at such a distance apart that the rope will, when strained around the several 60 pulleys and both ends fastened, fill the bottom of the bedstead as shown in Fig. 2, and if the rope be strained or drawn tightly around the several pulleys a good bed bottom will be obtained, each length of rope that 65 traverses across the bed being allowed to yield, turn or swing independently so as to accommodate itself to the movements or position of the body, and the bottom therefore is rendered perfectly flexible. The rope C, has its lengths connected by elastic bands e . 70 These bands during summer when a comparatively hard bottom is generally desired are not of much use, as the rope is strained or drawn sufficiently tight to prevent the several lengths of rope from moving too freely 75 in a lateral direction, but during winter when a softer bottom is desirable and the rope C, relaxed the elastic bands are very essential as they serve as guides or stays to the rope.

I am aware that pulleys have been placed 80 on pins attached to the rails of bedsteads to serve merely as friction rollers or pulleys to ease and facilitate the adjusting of sacking bottoms to bedsteads; but I am not aware that rollers have been attached to bedstead 85 rails as herein shown and a rope passed around said pulleys as described, so as to form a flexible and yielding bed bottom.

I do not claim broadly therefore the employment or use of friction rollers, but 90

What I do claim as new and desire to secure by Letters Patent, is,

1. The pulleys B, attached to two opposite sides or ends of the bedstead by cords, straps or equivalent means so as to admit of 95 the free turning of the pulleys and the twisting of the same in planes at right angles with their plane of rotation, in combination with the rope C, which is strained around the pulleys, the whole being arranged as and for 100 the purpose set forth.

2. I also claim in combination with the pulleys B, and rope C, the elastic bands e , for the purpose specified.

J. M. NOBLE.
